FOLDING CATHETER TRAY

Alvin J. Newell, Zion, Ill., assignor to Abbott Laboratories, Chicago, Ill., a corporation of Illinois

Filed Apr. 2, 1969, Ser. No. 16,560

Term of patent 14 years

Int. Cl. D24—02

U.S. Cl. D83—1

FIG. 3

FIG. 1

FIG. 2

FIG. 4

FIG. 5

FIG. 1 is a perspective view of a catheter tray of my new design in an extended position;

FIG. 2 is a top plan view thereof; with portions broken away for ease of illustration;

FIG. 3 is an end elevational view thereof as viewed along the line 3—3 of FIG. 2;

FIG. 4 is a side elevational view of the catheter in a folded position as viewed along the line 4—4 of FIG. 5; and

FIG. 5 is a top plan view of the catheter tray in a folded position.

I claim:

The ornamental design for a folding catheter tray, substantially as shown and described.
